Specification for Design.

Patented July 28, 1914.

Application filed May 11, 1914. Serial No. 837,950. Term of patent 14 years.

To all whom it may concern:

Be it known that we, THEODORE R. TREIBER and JOSEPH W. JOHNSON, citizens of the United States, residing at Kansas City, in the county of Jackson and State of Missouri, (whose post-office address is No. 1226 Main street, Kansas City, Missouri,) have invented a new and original and ornamental Design for Pool-Table Pockets, of which the following is a specification, reference being had to the accompanying drawing, forming part thereof.

We claim:—

The ornamental design for a pool table pocket, as shown,

THEODORE R. TREIBER.
JOSEPH W. JOHNSON.
